UNITED STATES PATENT OFFICE.

LEWIS T. WILCOX, OF PEEKSKILL, NEW YORK.

GRATE.

Application filed February 19, 1927. Serial No. 169,444.

This invention relates to grates to be placed over the burner holes in the tops of stoves and more particularly over the more remote opening in a stove top in which a plurality of openings are associated with a single burner.

In the past, burner openings were customarily covered with an open grid set into the opening so as to be substantially flush with the upper surface thereof, no attempt being made to influence the flow of heat in any manner by the grid, the grid merely being used as a means of supporting a vessel over the burner opening.

It is the purpose of this invention to provide a grate or grid which will assist in directing and controlling the flow of heat from a burner to the vessel which is being heated. It is also within the contemplation of this invention to provide a grate which will increase the flow of heat as well as direct it to definite areas in predetermined quantities.

These objects are accomplished by forming the grid with baffle vanes and baffle walls to direct the flow of heat and by forming the grate of such dimensions that it will support a vessel slightly above the surface of the stove top and thereby create an increase in the draught resulting in greater flow of heat. This latter feature is of particular application where one burner is utilized to supply the heat for a plurality of openings and with a grate construction in accordance with this invention, the entire flow of heat is used to its maximum efficiency.

In the drawings there is illustrated an embodiment of this invention, and in which: Fig. 1 is a perspective view of a grate member made in accordance with this invention;

Fig. 2 is a longitudinal section through the center of a grate member installed in a stove having two burner openings supplied by a single burner, and

Fig. 3 is a section on line 3—3 of Fig. 2.

For purposes of illustration, a circular disk-like grate 1 customarily made of cast iron has been shown having a substantially open center portion 2 and closed side portions 3 and 4 which serve as baffle portions. The inner edges of each of the baffle portions 3 and 4 are formed with perpendicular flanges or baffle webs 5 and 6 respectively, which webs extend a substantial distance

above and below the plane of the disk and closed portions 3 and 4. Similar baffle vanes 7 and 8 are formed integral with the grate extending from front to rear of the grate 60 across the open center portion and parallel to the webs 5 and 6. Vanes 7 and 8 also project above and below the surface of the closed portions 3 and 4 of the grate. Surrounding the rear and sides of the periphery 65 of the grate is an upstanding vertical baffle wall 9, the wall being continuous at the rear portion of the grate and interrupted or serrated at the side portions as at 10 and stops short of the front portion.

The upper edges of vanes 7 and 8 and of webs 5 and 6 are serrated as at 10, the uppermost portions all being in the same plane and in the same plane with the upper edge of baffle wall 9 so that a vessel may be supported thereupon for heating. The grate is formed with a projecting lug 11 on the underside at the rear thereof which is adapted to engage a recess in the stove top 12 to position the grate.

Referring particularly to Figs. 2 and 3, a grate constructed in accordance with this invention is shown as applied to an oil stove wherein a single burner 13 is utilized to supply heat through two openings 14 and 15 in a stove top 12. The heat is conducted through the openings by means of a heat collector 16 shown and described in detail in my application for patent Serial No. 169,446.

The front opening 14 is covered by the usual flush grate 17 set into a depression in the top 12, which grate will support a vessel over the front opening. The rear opening is covered by the grate 1 constructed in accordance with this invention and a vessel supported on top of the grate is held above the surface of the stove top 12 upon the raised webs 5 and 6, vanes 8 and wall 9, creating a draught thereby and inducing a flow of heat from the burner 13 up and through the grate 1, the front opening being closed by the vessel thereover.

The flow of heat is indicated by the arrows in Figs. 2 and 3 from which it follows 105 that as the heated air commonly referred to as heat rises from the burner it strikes the front portion of the top of the stove and the vessel thereon and is deflected and directed by the top 12 of the stove and the heat collector 16 to the rear opening 15. The closed or side baffle portions 3 and 4 direct

the heat through the center of the grate, the webs and vanes assisting in keeping the heat evenly distributed and preventing excessive side eddy currents. As the heat continues in its upward path, induced by the draught created by the raised vessel, some of its strikes the rear wall 9 and is deflected forwardly again over the under surface of the vessel whereupon it passes between the 10 serrations in the vanes and webs and not through the openings in the side portions of the baffle wall 9.

It follows therefore that the grid not only assists in inducing a current of heat but in 15 distributing and controlling the flow of the same in a manner whereby it is applied most efficiently to the vessel placed thereover. The grate may readily be removed for cleaning purposes and replaced with assurance 20 that it will be in proper position due to the positioning lug.

It is obvious that various changes may be made in the details of structure without departing from the spirit and scope of this 25 invention as defined in the appended claims.

I claim:

1. A grate for a stove comprising a ring-like member having baffle vanes extending thereacross and projecting above and below 30 the surface of said member to direct heat therethrough and support a vessel thereupon, said vanes being serrated upon the upper edge thereof to permit lateral flow of heat when a vessel is supported thereupon.
2. A grate for a stove comprising a disk-like member having an open center portion and imperforate side portions, baffle vanes extending from front to rear across said open center portion and a baffle wall extending 40 around the rear portion of said member.
3. A grate for a stove comprising a disk-like member having an open center portion and imperforate side portions, baffle vanes extending from front to rear across said 45 open center portion and projecting above the plane of said disk member and a baffle wall extending around the rear portion of the periphery of said member.
4. A grate for a stove comprising a disk-like member having an open center portion and imperforate side portions, baffle vanes extending from front to rear across said open center portion and projecting above said 50 disk member and a baffle wall extending around the rear portion of said member and projecting upwardly therefrom.

5. A grate for a stove comprising a disk-like member having an open center portion and imperforate side portions, baffle vanes extending from front to rear across said 60 open center portion and projecting above the plane of said disk member, the upper edges thereof being serrated to permit lateral flow of heat, and a baffle wall extending around the rear portion of said member and projecting 65 upwardly therefrom.

6. A grate for a stove comprising a disk-like member having an open center portion and imperforate side portions, baffle vanes extending from front to rear across said 70 open center portion and projecting above the plane of said disk member and a baffle wall extending around the rear portion of said member and projecting upwardly therefrom substantially the same distance of said 75 vanes, the vanes and said wall serving as a support for a vessel.

7. A grate for a stove comprising a disk-like member having an open center portion and imperforate side portions, baffle vanes 80 extending from front to rear across said open center portion and projecting above said disk member and a baffle wall extending around the rear portion of said member and projecting upwardly therefrom substantially the same distance as said vanes, the 85 vanes and said wall serving as a support for a vessel, said disk-like member having a projection extending therefrom adapted to cooperate with said stove to position said 90 grate.

8. A grate for a stove comprising a disk-like member having an open center portion and imperforate side portions, baffle vanes extending from front to rear across said 95 open center portion and a baffle wall extending around the rear and sides of the periphery of said disk member, the rear portion of said wall being continuous and the side portions being interrupted.

9. A grate for a stove comprising a disk-like member having an open center portion and imperforate side portions, said side portions terminating in baffle webs projecting above said disk members, baffle vanes extending from front to rear across said open center portion and a baffle wall extending around the rear portion of said member.

In witness whereof, I hereunto subscribe my signature.

LEWIS T. WILCOX.
